(57) **CLAIM**

The ornamental design for a vacuum cleaner body as shown and described.

DESCRIPTION

FIG. 1 is a front, right and top perspective view of a vacuum cleaner body showing our new design;

FIG. 2 is a rear, left and bottom perspective view thereof;

FIG. 3 is a front elevational view thereof;

FIG. 4 is a rear elevational view thereof;

FIG. 5 is a top plan view thereof;

FIG. 6 is a bottom plan view thereof;

FIG. 7 is a left side elevational view thereof;

FIG. 8 is a right side elevational view thereof; and,

FIG. 9 is a front, right and top perspective view of the vacuum cleaner body in accordance with our new design illustrating a state in which environmental structures are attached to the vacuum cleaner body.

The broken lines in the drawings illustrate the environmental structures or portions of the vacuum cleaner body which form no part of the claimed design.

1 Claim, 9 Drawing Sheets
